UNITED STATES PATENT OFFICE.

ALBERT J. GIFFORD, OF SHREWSBURY, MASSACHUSETTS.

SHOE HEEL REINFORCEMENT.

Application filed July 26, 1921. Serial No. 487,723.

To all whom it may concern:

Be it known that I, ALBERT J. GIFFORD, a citizen of the United States, residing at Shrewsbury, in the county of Worcester 5 and State of Massachusetts, have invented a new and useful Shoe-Heel Reinforcement, of which the following is a specification.

This invention relates to the reinforcement of a wooden shoe heel, and the principal object thereof is to provide a simple and inexpensive strengthening means, which can be applied easily, and will act to hold itself in position and not have any tendency to become loosened.

15 The invention is capable of application to wooden shoe heels of any kind, but is especially adapted for the high or French style.

Reference is to be had to the accompanying drawings, in which—

20 Fig. 1 is a longitudinal central sectional view of a wooden shoe heel with a preferred embodiment of this invention applied thereto;

Fig. 2 is a transverse longitudinal sectional view of the same on the line 2—2 of Fig. 1, and

Fig. 3 is a view of the strengthening wire or staple before its application to the heel.

The lower narrow part of the ordinary 30 high or French heel is apt to break on account of its form and the rough usage to which it is subjected, and especially on account of the fact that, as made, the grain of the wood runs crosswise at this point, so 35 that a slight crack is likely quickly to become a cross split in use. This invention is designed to provide a practical form of metallic strengthening device for such a heel.

The invention involves the provision of a 40 pair of longitudinal passages 10 through the heel 12, preferably diverging from each other toward the bottom, but located in a single plane. This plane is located in the center of the heel substantially as indicated 45 in Fig. 1. I prefer to have the two passages extend through the heel into an open space 11 near the top.

The strengthening piece consists of a 50 length of wire 13 which is bent at the center and folded back upon itself to form it into the shape of a staple. The wire preferably is kept at the same diameter in size throughout its length and, after the holes 10 are

drilled, it is introduced from the top and driven in clear up to the loop or bridge 14 55 at the top of the strengthening wire or staple.

It will be noticed that the piece of wire 13, in its original form, has parallel legs spaced only a short distance apart. When forced 60 into the passage 10 the free ends of these legs are forced apart and the natural resiliency of the wire will tend to bring them together so that they grip the wood between the two passages. This tends to hold the 65 staple in place and avoids all necessity of providing any special provisions, such as heads on the bottom ends of the wire or irregularities on the surfaces where they are embedded in the wood. Furthermore, 70 there is no danger of the wire coming out or either one of the strengthening legs becoming loosened, or failing to perform its function. The wire extends across the grain of the heel as it is ordinarily made, and 75 prevents the cracking of the heel across it in the direction of its grain.

It will be noted that each of the legs of this staple in itself is a strengthener, and that it is held in position by the fact that 80 it is bent over at the top and extends down into the heel on the other side, no matter if the second leg does not extend clear through to the bottom. The fact that the staple is originally made with its two parts parallel 85 and is forced into the diverging passages is relied upon as stated above for securely holding the device in place.

In case the heel does crack across the wire legs will hold it on and also prevent 90 the bottom from turning. This is due to the fact that the two legs are integral, resilient, and divergent.

The simplicity with which the device can be made and especially with which it can be 95 put in place, is an important feature of this invention. The fact that only one wire is used so that the two strengthening bars are provided with only one handling and no danger of either part being displaced during 100 its introduction in place, or after it is located in position, is also an important practical consideration.

Although I have illustrated and described only a single form of the invention, I am 105 aware of the fact that modifications can be

2
made therein by any person skilled in the art without departing from the scope of the invention as expressed in the claims.

Therefore, I do not wish to be limited to 5 all the details of construction herein shown and described, but what I do claim is:—

1. As an article of manufacture, a wooden shoe heel having a single wire extending through it vertically, said wire having two 10 legs connected together between the top and bottom of the heel, for strengthening the heel.

2. As an article of manufacture, a wooden shoe heel having a wire in the form of a 15 staple driven in from the top and extending along it vertically across the grain for strengthening it.

3. As an article of manufacture, a wooden

shoe heel having a wire extending through it for strengthening purposes, and provided 20 with an integral end bent over at the top and extending down into the heel for helping to hold it in position.

4. As an article of manufacture, a wooden shoe heel having a pair of passages extending 25 substantially vertically therein but diverging from each other toward the bottom, and a wire bent to staple form with parallel legs forced into said passage so that the natural resiliency of the wire will tend to 30 hold it in position when forced to assume the relative position due to the diverging passages.

In testimony whereof I have hereunto affixed my signature.

ALBERT J. GIFFORD.
